UNITED STATES PATENT OFFICE.

JOHN MCTAMMANY, OF STAMFORD, CONNECTICUT.

MACHINE FOR PRINTING MASTER-SHEETS FOR TYPE-WRITER OPERATORS, &c.

1,075,366.

Specification of Letters Patent.

Patented Oct. 14, 1913.

Application filed February 7, 1912. Serial No. 676,143.

To all whom it may concern:

Be it known that I, JOHN MCTAMMANY, a citizen of the United States, and a resident of Stamford, in the county of Fairfield and State of Connecticut, have invented certain new and useful Improvements in Machines for Printing Master-Sheets for Type-Writer Operators, &c., of which the following is a specification.

10 This invention relates to machines for producing master-sheets adapted for use in connection with automatic mechanical type-writer operators, mechanical musical instruments, etc.

15 A master-sheet for a typewriter operator is provided usually along its longitudinal center with rows of feed perforations adapted to engage feeding projections on the feed roll of a perforating machine employed to perforate the sheet to provide typewriter key-operating perforations therein, the said operating perforations being formed subsequently to the formation of the feed perforations. The operating 20 perforations are formed in accordance with the matter to be typewritten, each operating perforation occupying a different position lengthwise of the sheet from all the others. Heretofore, the sheet has not been provided 25 with designating characters by which the operating perforations may be read, so that the printed matter which they are designed to produce cannot be readily determined by a quick inspection of the sheet.

30 My invention has for its object to provide a machine adapted to apply to the sheet, printed matter which will enable the operating perforations subsequently formed on the sheet to be easily read, the printed matter 35 being arranged in a definite and unvarying predetermined relation to the feed perforations of the sheet, and to the spaces intended for the operating perforations subsequently formed.

40 The invention consists in the improvements which I will now proceed to describe and claim.

45 Of the accompanying drawings: Figure 1 represents a top plan view of a machine embodying my invention, parts being broken away; Fig. 2 represents a section on line 2—2 of Fig. 1; Fig. 3 represents a side elevation of the machine; Fig. 4 represents a section on line 4—4 of Fig. 1; Fig. 5 represents partly in elevation and partly in

section the punching mechanism hereinafter described; Fig. 6 represents a section on line 6—6 of Fig. 1; Fig. 7 represents a view of a fragment of the central portion of a master-sheet and shows the printed characters impressed thereon by the embodiment of my machine shown by the preceding figures.

50 The same reference characters indicate the same parts in all the figures.

The supporting frame of my machine includes a base 12 having a bed 13 over which the paper sheet 14 to be printed is drawn by a feed roll 15 journaled in bearings at one end of the machine. Said feed roll is provided at its central portion with radial feeding pins 16 adapted to enter perforations 17, (Fig. 7) formed along the central portion of the sheet 14. Said perforations may be formed in the sheet before it is acted on by the machine of my invention, but I prefer 55 to provide the machine with punching mechanism adapted to form the perforations 17, as hereinafter described. The engagement of the feeding projections 16 with the feed perforations 17 of the sheet causes 60 a positive engagement between the feed roll and the sheet, so that the sheet cannot move independently of the feed roll, and so that the printing couples which are geared to the feed roll as hereinafter described, will do 65 their work accurately with relation to the said perforations 17.

65 18 and 19 represent the members of a printing couple arranged to bear on opposite sides of the portion of the sheet which is 70 located over the bed 13. The member 19 is a bed roll located in an opening in the bed 18, its highest point being substantially flush with the surface of the bed. The member 18 is a type wheel provided with 75 raised printing characters 21 which, in a machine for printing master sheets for type-writer operators, will include the letters of the alphabet and other characters usually printed by ordinary typewriters. The portion of the member 18 shown by Fig. 1 is provided with type to print the letters of the alphabet, the types being arranged in peripheral rows and each row including 80 types of the same character, the types of each row differing from those of the other rows, as indicated, so that the operation of the printing couple on the sheet causes the printing of corresponding letters on the sheet in rows extending lengthwise thereof, 85 90 95 100 105 110

as indicated by Fig. 7. The types of the member 18 are inked by an inking roll 22 located above the member 18.

The embodiment of my invention here shown include additional printing couples 23, 24 and 25, 26. The member 24 is provided with longitudinal radial rule printing projections 27 adapted to print transverse lines on the sheet 14, and the member 26 is provided with peripheral circular rule projections 28 adapted to print longitudinal lines on the sheet 14, the said transverse and longitudinal lines intersecting and subdividing the sheet into squares. The several printing couples are geared together and to the feed roll and operated in unison, as herein-after described, the arrangement being such that the characters printed by the member 18 occupy an accurate predetermined relationship to the lines printed by the members 24 and 26, the printed characters being preferably within alternate squares extending lengthwise of the sheet, as shown by Fig. 7.

30 represents a driving shaft which may be continuously rotated by any suitable means.

31 represents a fixed punch bed or die which may form a part of the bed 13 and 30 is located between the printing couples and the feed roll.

32 represents a gang of punches attached to a reciprocating carrier 33 which is movable in a fixed vertical guide 34, and is reciprocated by an eccentric 35 affixed to the driving shaft 30, and a strap 36 surrounding said eccentric and pivoted at 37 to the punch carrier 33. The eccentric and strap are caused by the rotation of the driving shaft to alternately lift and depress the punch carrier and punches, the latter cooperating with the die when they descend in forming a number of the feed perforations 17 in the sheet 14.

45 Mechanism is provided for intermittently rotating the feed roll and the printing couple members in unison, and for causing the operation of the punching mechanism while the feed roll and printing members 50 are at rest, the said mechanism being 55 organized to cause an accurate or predetermined relation between the printed matter and the feed perforations 17, said mechanism in the embodiment of my invention here shown being organized as follows: 38 represents a mutilated gear attached to the driving shaft 30 and preferably composed of a disk having a single gear tooth 39. 40 represents a gear wheel having elongated 60 teeth provided with inwardly curved outward faces 41 and separated by notches 42, each adapted to engage the gear tooth 39. The gear 40 is mounted to rotate on a stud or bearing 44, and to it is attached a spur gear 45 which forms a part of a train of

gearing which imparts motion from the driving shaft to the feed roll and to the members of the several printing couples. The gears 38 and 40 constitute a well known form of segmental intermittent feed motion, 70 the continuously rotated or driving gear 38 having an operative movement during only a small part of a complete rotation, the movement during a greater part of a rotation being a dead movement. The recessed faces 41 of the gear 40 engage the periphery of the disk portion of the gear 38 so that the gear 40 is locked during the dead movement of the gear 38. The spur gear 45 is attached to the gear 40 and is rotated intermittently thereby, said gear 45 being connected with the feed roll 15 by an intermediate gear 46 meshing with a gear 47 on a shaft 48 of the feed roll. To the shaft 48 is attached a smaller gear 49 meshing with a larger gear 50, which in turn meshes with a smaller gear 51 attached to the shaft 52 of the printing couple member 25. The gear 51 meshes with a gear 53 attached to a shaft 54 of the printing couple member 26. 80 The described gearing is organized to rotate the printing couple members 25 and 26 in the directions indicated by the arrows in Fig. 4. The shaft 55 of the inking roll which supplies the printing couple member 26 is provided with a gear 56 meshing with the gear 53. The gear 51 attached to the lower printing couple member 25 is connected by a gear 57 with a gear 58 attached to the shaft of the printing couple member 23. The printing couple members 23 and 24 and 19 and 18 are geared together in the same manner as the printing couple members 25 and 26 and the gears of the lower couple members 23 and 19 are connected by an intermediate gear 59 so that the members of each couple are rotated in unison in the directions indicated by the arrows in Fig. 4.

It will be seen that the described mechanism provides for the accurate location of the printed character on the sheet with reference to the feed perforations 17 formed therein and to the squares printed on the sheet by the couples 23, 24, 25, 26, so that 115 when the sheet is subsequently passed through a perforating machine to receive operating perforations, the latter will be accurately located with reference to the printed squares and characters and to the feed perforations. Again, when the perforated master-sheet is applied to a typewriter operator, the operating perforations will be caused to occupy the desired relation to the parts of the operator controlled thereby in 120 actuating the typewriter keys. A master-sheet having feed perforations and printed matter, as herein shown, is adapted particularly for use in connection with the perforating machine and the automatic typewriter 125 130

operating machine set forth in two applications for Letters Patent of the United States filed by me concurrently herewith, Serial Nos. 676,145 and 676,144. The paper supplied to the machine may be stored on a magazine roll 62 supported by bearings 63 at one end of the base 12.

It is obvious that if the sheet 14 is perforated before it is acted on by the printing mechanism, the punching mechanism above described being omitted, the intermittent feed motion may be dispensed with and the feed roll and printing couples continuously rotated. This may be accomplished by gearing the driving shaft 31 directly to the train of gears which transmits motion therefrom. It is also obvious that the printing couples which print the longitudinal and transverse lines, or either of said couples may be omitted so that only the characters printed by the member 18, or only said characters and one set of lines will be printed on the sheet.

When the operating perforations are formed in the printed sheet, they will bear a predetermined relation to the printed characters thereon. For example, a perforation intended to cause the printing of the letter "S" by a typewriter will be located in a space between two printed letters of the "S" row, Fig. 7, while a perforation intended to cause the printing of the letter "T" will be located in a space between two printed letters of the "T" row. The letter or character represented by each operating perforation is therefore clearly indicated by adjacent printed characters on the sheet. The feed perforations 17 are formed in the same transverse row of squares as the printed characters, but are smaller than the latter, so that the characters are not rendered illegible by the perforations.

I claim:

1. A machine of the character stated comprising a feed roll having feeding projections for positively engaging feed perforations in a sheet moved thereby, a plurality of rotary printing couples between the members of which the sheet is moved by the feed roll, said couples being adapted to jointly print spaced characters and elongated lines on the sheet, and gearing connecting the printing couples and connecting the feed roll with the printing couples, to

determine the relationship of the characters and the printed lines to the feed perforations in the sheet.

2. A machine of the character stated comprising a feed roll having feeding projections for positively engaging feed perforations in a sheet moved thereby, a rotary printing couple the members of which are arranged at opposite sides of the path of a sheet moved by the feed roll, the printing characters differing from each other in the direction of the axis of rotation of the printing couple and being duplicates in the plane of rotation, sheet punching mechanism, and operating mechanism having means for intermittently rotating the feed roll and printing couple members in unison, and for operating the punching mechanism while the said feed roll and couple members are at rest, the said mechanism being organized to cause a predetermined relation between the printed matter on the sheet and the perforations therein.

3. A machine of the character stated comprising a feed roll having feeding projections for positively engaging feed perforations in a sheet moved thereby, a rotary printing couple, the members of which bear on opposite sides of the sheet, the printing characters differing from each other in the direction of the axis of rotation of the printing couple and being duplicates in the plane of rotation, sheet punching members between which the sheet is drawn by the feed roll, one of said members being fixed and the other movable, a continuously rotated driving shaft, connections between the shaft and the movable punching member whereby the latter is reciprocated, and a train of gearing connecting the driving shaft with the feed roll and with the members of the printing couple, and adapted to move the said feed roll and couple members in unison, said train being provided with an intermittent feed motion for intermittently rotating the feed roll and printing couple members, and timed to hold the sheet stationary while the punching members are operating.

In testimony whereof I have affixed my signature, in presence of two witnesses.

JOHN McTAMMANY.
